UNITED STATES PATENT OFFICE

WILLIAM H. HIDLEBAUGH, OF ELECTRA, TEXAS

TRAIN LINE COUPLER

Application filed June 12, 1931. Serial No. 543,955.

This invention relates to new and useful improvements in air line couplers for railway brake systems.

One object of the present invention is to provide a novel and improved means for effectively forming a connection between the air line, of the couplers, when said couplers are properly brought together.

Another object is to provide a device of this character wherein the outer end of the air hose of the train line is so constructed and arranged that it will automatically engage with a similar end on the coupler of another car, whereby to effectively form the connection and continuation of the air passage.

Another object is to provide a device of this character wherein the air line ends are properly engaged prior to the opening of the valve of the line, whereby to prevent escape of air during the coupling operation.

Other objects and advantages will be apparent from the following description when taken in connection with the accompanying drawings.

In the drawings:

Figure 1 is a top plan view of the coupling heads of two railway cars, embodying the present invention.

Figure 2 is a side elevation of the same.

Figure 3 is a horizontal longitudinal sectional view on the line 3—3 of Figure 2.

Figure 4 is a sectional view, similar to that of Figure 3, but showing the coupling heads partly engaged.

Figure 5 is a vertical longitudinal sectional view on the line 5—5 of Figure 1.

Referring particularly to the accompanying drawings, 10 and 11 represent two draw bars, which have in their outer ends the coupler heads 12 and 13, respectively, said coupler heads being mounted for lateral pivotal movement with relation to the draw bars, and held in centered position by the leaf springs 14, carried by the sides of the ends of the draw bars, and engaged with the side faces of said coupler heads, as clearly shown in the drawings. The inner end of each of the coupler heads is tapered, as at 15, and is formed with a cavity or chamber

16, therein, one end of which terminates in a nipple 17, to which is attached one end of the air hose 18, while the other end is open, as shown. The outer end of each coupler head 12 and 13 is formed with the recess 19, and the adjacent projection or nose 20. It will be noted that the recesses and noses of the coupler heads are so arranged that they interlock when said heads are brought into engagement, the nose of each fitting into the recess of the other. Formed transversely in the rear portion of each coupler head, at 21, is a passage, cylindrical in cross section, and communicating with the diametrically opposite sides of the intermediate portion of said passage are the passages 22 and 23, the former extending forwardly to communicate with the cavity or chamber 16, and the latter extending rearwardly to the smaller end of the coupler head. Connected to the said smaller end of the coupler head is one end of an air hose 24, the other end of which extends through the draw bar 11, and out through the side thereof, where it is adapted to be connected to the air line, not shown. Mounted in each coupler head, for lateral pivotal movement, is a hollow member 26, the inner end of which has connected thereto one end of a short length of air hose 27, which hose has its other end secured to the said nipple 17. The forward end of each of the members 26 projects a short distance beyond the nose of the coupler head, and is provided with a roller 28, on its outer end, for engagement with the opposite inclined wall of the recess 19, of the mating coupler head, whereby to cause the lateral swinging of said member, in a direction toward the center of the head, a spring 29 being connected to said member and to a wall of the chamber 16, to yieldably maintain said member, in normal position within the chamber. Each of the members 26 is hollow, and has a lateral outlet in its inner side face, adjacent the outer end of the member, as shown at 30, such outlet being provided with a suitable packing 31, whereby to form an air-tight joint with the other member, when the coupling heads are properly engaged. Disposed vertically through each coupler head 12

and 13, in intersecting relation to the passage 22, is a rotary plug valve 32, having a passage 33 for register with the passage 22, to permit flow of air to the members 26, and through the air line, as will be understood. 5
Mounted on one end of each of these valves 32 is a cam member 34, which is adapted to be engaged and rocked by a roller 35, mounted on the nose 20. It will be noted that the cams 34 of the heads 12 and 13 are arranged on the upper sides thereof, and that the rollers 35 are also arranged on the upper portions, for proper engagement, to rock the cams, upon engagement of the couplers. A 10
spring 36 holds each cam 34 in place. 15

In each passage 21 is disposed a rotary plug valve 37, having a transverse passage for register with the passages 22 and 23, the ends of said valve being provided with 20 suitable operating rods 38.

Normally the valves 32 are in closed position, by the action of the springs 36, and the members 26 are held in one lateral position by their springs 29. When the coupler heads 25 are brought together, the nose of each enters the recess of the other, while the rollered end of each member 26 enters the chamber 16 of the other head, so as to engage its roller with the inclined wall of said chamber, and 30 thereby be shifted to one side, against the tension of their springs 29. This movement of the members 26 brings their packed outlets into firm contact with each other, whereby to establish a continuous passage through 35 these members. Subsequent to the contact of the packed outlets of the members 26, the rollers 35 engage the cams 34, and rock them, against the tension of their springs 36, whereby to rotate the valves 32 so as to register 40 their transverse passages with the passages 22 and 23, and thus establish a complete channel for the air of the air line. When the coupler heads are pulled apart, the cams 34 are released from the rollers, 45 whereby to close the valves 32, prior to the separation of the members 26, so that there will be no danger of escape of air from the train line, which would otherwise reduce the pressure to an extent sufficient to apply 50 the brakes.

What is claimed is:

An air line coupler comprising mating coupling heads each having a recess opening through its outer end and a longitudinal air 55 passage through the other end communicating with said recess, a wall of said recess being inclined, a laterally swingable member in the recess having a longitudinal air passage opening through an end and a side 60 thereof, means for holding said member in its normal outward position, the air passage at the end of said member being connected with the adjacent end of the air passage of the head, and a roller on the outer end of said member for engagement with

said inclined wall, upon mating of said coupling heads, whereby to register the laterally opening ends of the swingable members of said coupling heads to form a continuous air passage therethrough. 70

In testimony whereof, I affix my signature.
WILLIAM H. HIDLEBAUGH.
